UNITED STATES PATENT OFFICE.

CHARLES M. SEXTON, OF AURORA, ILLINOIS.

COMBINED LATCH AND CATCH FOR DOORS.

977,137.

Specification of Letters Patent. Patented Nov. 29, 1910.

Application filed September 13, 1910. Serial No. 581,889.

To all whom it may concern:

Be it known that I, CHARLES M. SEXTON, citizen of the United States, residing at Aurora, in the county of Kane and State of Illinois, have invented certain new and useful Improvements in Combined Latches and Catches for Doors, of which the following is a specification.

This invention relates to devices for holding screen doors in closed position, and operating both as a "latch" and a "catch" to prevent doors from rattling when closed, and likewise preventing them from being opened too easily, at the same time yieldable to a sufficient extent to enable the door to be readily operated.

The principal object of the invention is to simplify and improve the construction and increase the efficiency and utility in devices of this character, and with this and other objects in view, the invention consists in certain novel features of construction, hereinafter described; and, then specifically pointed out in the claim, and in the drawings illustrative of the preferred embodiment of the invention.

Figure 1 is a side elevation of a portion of a door frame and its casing, together with a portion of a screen door with the improvement applied. Fig. 2 is a transverse section on the line 2—2 of Fig. 1. Fig. 3 is an enlarged side elevation of the improved device applied to the portion of a door casing.

The improved device comprises a combined latch and catch formed of a resilient body adapted to be connected at its ends to the door casing, and projecting intermediate its ends into the path of the door, so that the door when opened and closed will engage the projecting portion of the device and compress it as the door passes either in opening or closing.

The improved device is preferably formed from a single piece of wire bent into a plurality of coils with eyes at the ends to receive the holding screws and with the intermediate portion of the coils the largest, as shown more particularly in Fig. 3, wherein the intermediate coils are represented at 10, the terminal eyes at 11 and the holding

screws at 12, the screws being inserted into the casing at the latch side of the door represented at 13. The coils 10 are gradually enlarged from each end toward the center, 55 as shown in Fig. 3, and the device is so attached to the casing 13 that the central enlarged coils project beyond the jamb portion of the casing or door frame and into the path of the door, represented at 14, when 60 the latter is opened and closed. The member 10 being formed of resilient material will yield under the pressure of the door and permit the door to pass, and then when the door is closed the device will again yield 65 and permit the door to pass, but will immediately and automatically project again into the path of the door and prevent it from opening unless a sufficient force is applied to overcome the resistance of the coils. 70

It will thus be noted that a simply constructed and effectually combined latch and catch is produced, which effectually supports the door in closed position, and at the same time is yieldable to permit the door to be 75 opened. The resiliency of the device is sufficient to prevent a door from being accidentally opened by wind or other similar cause.

The improved device may be constructed of 80 any suitable wire, japanned, bronzed, or otherwise coated or treated, either for ornamental or protective purposes, and may be varied in size to correspond to the size of the door to which it is to be applied. 85

Having thus described my invention, what is claimed as new is—

As a new article of manufacture, a combined latch and catch for doors formed of a coil of wire, greatest in diameter intermediate its ends, and with means at the ends for attachment to a door casing, with the larger intermediate portion of the coil extending into the path of a door and engaged thereby when same is opened and closed. 95

In testimony whereof, I affix my signature in presence of two witnesses.

CHARLES M. SEXTON. [L. S.]
